UNITED STATES PATENT OFFICE.

WILLIAM C. HIERING, OF NEWARK, NEW JERSEY, AND EMIL J. WALTER, OF NEW YORK, N. Y., ASSIGNORS TO J. E. MERCOTT CO., OF NEWARK, NEW JERSEY, A CORPORATION OF DELAWARE.

BAG-FRAME FASTENER.

Application filed July 31, 1924. Serial No. 729,234.

This invention relates to bag frame securing devices and more particularly to such types as are provided with snap catches in addition to a positive locking means.

5 One of the objects of the invention is in the provision of a frame having rigid raised parallel plates arranged in register on each frame side, one of the plates having an opening to receive a spring knob carried by 10 the mating side whereby the sides are normally held in closed relation.

A further purpose is to provide in the same plates a positive lock, actuated by a handled rotary element, whereby the frame 15 sides are held in fixed engagement until voluntarily released by definite action.

Another aim is in the production of a double engaging means for fastening a bag frame, one being spring actuated and the 20 other manually controlled, both being effective and tending to embellish the bag without materially increasing the cost of construction.

These several objects are attained by the 25 novel construction and combination of parts hereinafter described and shown in the annexed drawing, forming a consequential part of this disclosure, and in which:

Figure 1 is a fragmentary side elevational 30 view of a conventional type of bag frame, showing the application of the invention.

Figure 2 is a transverse sectional view taken on line 2—2 of Figure 1.

Figure 3 is a longitudinal sectional view 35 taken on line 3—3 of Figure 1, parts being omitted to avoid confusion.

Figure 4 is a rear elevational view of one of the locking plates in detail.

Referring more in detail to the drawing, 40 the numerals 10 and 11 designate the respective bag frame side members, which are of the usual channelled type connected at their angularly turned lower ends by hinges, not shown, and composed of sheet metal die formed into the customary shape.

The frame side 10 has a rigid upstanding plate 12 die struck from sheet metal and presenting any approved outline, including a level base from which project prongs 13 50 suited to enter corresponding perforations in the upper element of the frame side to be

firmly and permanently upset and riveted therein.

A circular opening 14 is formed through the center of the plate 12, in its upper portion this opening being adapted to receive over its lower edge a snap fastener comprising a spherical head 15 at the end of a bent stem 16 formed centrally at the upper edge of a plate 17, extending coincident in length 60 and parallel with the plate 12, but of a lesser height, the plate 17 being rigidly fixed on the frame side 11 by prongs 18 in the manner previously described.

Formed in the plate 17 below and in register with the stem 16, is a slot 19 having a square top and open at the bottom or base edge of the plate.

The plate 12 is pierced in register with the slot 19 to rotatably receive a spindle 70 20 having at one end an enlarged circular head 21 drilled upon opposite sides to receive a pair of inturned lugs 22 formed on the forked portion of a handle 23 normally pendant due to its pivoted connection with 75 the head.

A knob 24, on the other end of the spindle 20, is flattened on one side, as at 25, so that when the spindle is rotated by its handle to bring the flattened side uppermost, it may 80 be passed through the slot 19 and thereafter, by turning the spindle, the overhanging shouldered portion of the knob may be engaged with the outer surface of the plate 17, above the slot in the manner of a catch 85 bolt.

The spindle is held from moving lengthwise in the plate 12 by a collar 26 brazed or otherwise rigidly secured to it, the collar being seated on the inner side of the plate 90 12 and is guided circumferentially by a plate bent into a substantial U shape, one forked prong 27 of which is disposed on the inner side of the plate 12, its loop 28 passing through a recess in the bottom edge of the 95 plate and the other prong 29 is pressed against the outer side of the plate 12.

Pressing against the inner shouldered end of the spindle head 21 is a bent flat spring 30, its ends extending equally outward to 100 bear against the outer surface of the plate 12 and its upper portion bent inwardly to

provide stops 31 positively limiting the inward movement of the spindle.

The lowermost central portion 32 of the spring 30 is curved outwardly acting to reinforce or stiffen the central portion of the spring so as to present a flat bearing for the head 21.

In operation, to either open or close the bag, the handle 23 will be turned to rotate 10 the knob 24 a half turn, bringing the flattened portion 25 uppermost and then forcing the globular element 15 into or out of the opening 14 as may be required.

Obviously the element 15 acts as an efficient snap fastener in securing the bag frame sides, its action being pronounced and as effective as such types of fasteners can be made, operating without distorting the bag in any manner.

20 It will be further understood that when the locking knob 24 is in the position shown in Figure 2 the bag is positively locked to resist all attempts at intrusion until the knob is rotated into a releasing position.

25 Although we have described our improvements with considerable detail and with respect to a certain particular form of the invention, it is not desired to be limited to such details since many changes and modifications may well be made without departing from the spirit and scope of the invention in its broadest aspect.

Having thus described our invention, what we claim as new and desire to secure by Letters Patent, is:—

35 A combined catch and latch for bags, comprising in combination with a pair of hinged frames, of a raised flat plate secured at its edge to one of said frames, said plate containing a circular opening in its upper part, a second plate secured to the other frame parallel to the first plate, said second plate having a recess in its lower portion, a spherical knob on the second plate adapted to be sprung through the opening in the first plate, 40 a headed stem rotatable transversely in the first plate, a collar fixed on said stem, a channelled support embracing the first named plate, said support having an opening to guide said collar, a flat spring bowed 45 outwardly to extend interjacent the head of said stem and support, stops on said spring to positively limit inward movement of the stem, a flattened ball on said stem adapted to pass through the recess in the second plate 50 when in one position and engage the outer surface of the plate when said stem is rotated into another position, and a handle pivoted in the head of said stem whereby it may be rotated.

55 This specification signed this 24th day of July, 1924.

WILLIAM C. HIERING.
EMIL J. WALTER.
